DESIGN FOR A RACK

Irvin R. Linnard, Montclair, N. J.

Application June 17, 1947, Serial No. 139,748

Term of patent 14 years

(Cl. D33—16)

To all whom it may concern:

Be it known that I, Irvin R. Linnard, a citizen of the United States, residing at Montclair, in the county of Essex and State of New York, have invented a new, original, and ornamental Design for a Rack, of which the following is a specification, reference being had to the accompanying drawing, forming a part thereof.

In the drawing,

Fig. 1 is a perspective view of a rack showing my new design;

Fig. 2 is a top plan view; and

Fig. 3 is a side elevational view thereof.

I claim:

The ornamental design for a rack, as shown.

IRVIN R. LINNARD.
